UNITED STATES PATENT OFFICE

MAX FEINSTEIN, OF CORONA, NEW YORK, ASSIGNOR TO CHARLES MILLER, OF LONG ISLAND CITY, NEW YORK

SHOE LINING

Application filed February 12, 1930. Serial No. 427,695.

This invention relates to the shoe art and deals more specifically with a frictional lining for the heel portion of a shoe.

It is an object of this invention to provide a shoe having a lining containing, as an integral portion thereof, a frictional section at the heel.

It is a further object of this invention to provide a shoe having a lining which 10 forms correctly and smoothly to the interior of the shoe with a minimum of looseness and wrinkling.

Further, it is an object of this invention to provide a shoe having a lining in which there 15 is embodied a frictional section, and which lining is adapted to conform accurately to the interior of the shoe.

These and other objects of the invention will be readily apparent to those skilled in 20 the art from the following description taken in connection with the accompanying drawings, in which:

Fig. 1 is a plan view of a shoe embodying the present invention, certain elements of the 25 shoe being turned back for the purposes of illustration;

Fig. 2 is a view similar to that of Fig. 1 showing the turned back portions in place;

Fig. 4 is a fragmentary detailed view of a 30 lining embodying the principles of the present invention; and

Fig. 3 is a sectional view taken along the line 3—3 of Fig. 4.

Referring in detail to the drawings, the 35 shoe 10 is seen to comprise the usual upper 11, and insole 12. The lining 13, which may be formed of the usual materials, is provided with inserts 14 and 15 which are sewed to the lining 13 by lines of stitching 16 and 17 as 40 shown more clearly in Fig. 4. The lining 13 is held together by the line of stitching 18. Except for the stitching 18 the two halves of the lining are unattached to each other. The material used for the inserts 14 and 15 may 45 be of any well known frictional material now commonly used in the art, but preferably of a thin flexible leather with the skin side positioned for contact with the wearer's foot.

In practicing the present invention a lining 50 of the standard form is provided with the

inserts as described above and is sewed in place in the shoe with the overlapping adjacent free edges of the inserts as shown in the drawings. During the finishing operation of the shoe the overlapping edges of the inserts are smoothed down and the insole 12 placed thereover. While this invention has been described in connection with a shoe having an insole, it will be understood, of course, that this invention is particularly applicable to 55 shoes manufactured in accordance with the turn process in which event the member 12 would be a sock lining instead of an insole. As a matter of fact, in actual practice this invention has been found most suitable in 60 connection with the turn process for the reason that after the shoe is turned it is possible completely to smooth out the lining on 65 the inside of the shoe.

It will be readily understood, of course, 70 that various modifications of the present invention will readily suggest themselves to those skilled in the art. This invention, therefore, is not to be limited to the specific 75 details of structure disclosed except as defined in the appended claims.

Having thus described my invention, I claim:

1. In a shoe, a lining therefor, said lining 80 having inserts at the heel portion thereof, said inserts being free from each other along two adjacent marginal edges, and adapted to overlap when in place in the shoe.

2. In a shoe, a lining therefor, said lining 85 having inserts at the heel portion thereof, said inserts being free from each other along two adjacent marginal edges and being of a material having a frictional surface for contact with the wearer's foot, and adapted to overlap when in place in the shoe. 90

3. In a shoe, a lining therefor, the heel portion of said lining having a frictional surface for engaging the heel of the wearer, and the said heel portion having two adjacent free edges adapted to lie in overlapping relation when said lining is placed in the shoe. 95

4. In a shoe, a lining having two portions joined together at the heel portion of the said shoe, said lining also having at the heel portion a cut-out section, and inserts of material 100

attached to said lining at said cut-out section, said inserts having a frictional surface and having their adjacent ends overlapped and free of stitching when in place in the shoe.

5. In a shoe, a lining therefor, an insole, the said lining comprising two portions joined together at the heel portion of said shoe from a point at the top of said lining to a point intermediate of the top and bottom 10 of said lining, the adjacent edges of said lining between said last mentioned point and the bottom of said lining lying in overlapped relation in the shoe as assembled, and said overlapped edges being free of stitching.

15 MAX FEINSTEIN.
